UNITED STATES PATENT OFFICE.

WILLIAM GRAY, OF ROCHESTER, NEW YORK.

STOVE OR FURNACE PIPE.

Application filed May 26, 1921. Serial No. 472,713.

To all whom it may concern:

Be it known that I, WILLIAM GRAY, a citizen of the United States of America, and residing at Rochester, in the county of 5 Monroe and State of New York, have invented certain new and useful Improvements in Stove or Furnace Pipes, of which the following is a specification.

My invention relates to a stove or furnace 10 pipe, and has for its chief object to afford a structure that lends itself readily to packing and shipping.

Another object of the improvement is to afford a pipe section which can be packed in 15 nested relation with a number of sections, and which can easily and quickly be assembled when ready for use.

An additional purpose of the invention is to provide a form of T-pipe, whereby a number 20 of sections can be nested one within the other for packing, and thus be accommodated in a minimum space.

Still a further object of the improvement is to afford a simple, efficient and readily operated means for interlocking or retaining 25 together the separable walls of a section, when assembled for installation.

The invention also comprehends certain other features and advantages, all of which 30 will appear clearly from the following description, in conjunction with the accompanying drawing, the novel features being pointed out in the claim following the description.

35 In the drawing:

Figure 1 is a front elevation of a pipe section, embodying a preferred arrangement of the invention, and showing the separable walls interlocked;

40 Figure 2 is a side elevation of the same;

Figure 3 is a front elevation similar to Figure 1, and illustrating the relative positions of the separable walls as they are moved apart;

45 Figure 4 is a sectional view illustrating two pipe sections, with their walls separated, and one nested within the other for packing;

Figure 5 is a sectional view on the line 50 5-5 of Figure 1;

Figure 6 is a sectional view on the line 6-6 of Figure 1, and

Figure 7 is a sectional view on the line 7-7 of Figure 1.

55 The invention may be carried out in a number of different ways, and for purpose

of illustration, I have shown but one practical form, merely as an example of various adaptations that can be devised for accomplishing the same end. In the present disclosure, A designates the main portion of the pipe section, to which is secured a lateral flue portion B. The flue portion B is smaller in diameter at its outer end than at its base where it joins on to the main portion A, and 60 is tapering between its ends so as to permit nesting two flue portions B and B' within one another, as shown in Figure 4.

In order to permit such a nested arrangement, the main portion A is split longitudinally at a point substantially opposite to the flue portion B, thereby affording separable walls C and C', which can be spread apart, as shown in Figure 4, when the section is packed, or brought into interlocked 70 relationship, as shown in Figure 1, when the pipe is to be used. To this end, the wall C is bent upon itself longitudinally along its edge to afford a groove that receives a tongue 75 c, which extends longitudinally along the edge of the wall C'. This arrangement affords a close-fitting over-lapping joint, and the respective walls are held in this relation, as indicated in Figure 7, by the following interlocking means.

The groove in the wall C is provided with a recess or pocket c', which receives a projection or abutment c² formed on the wall C', and at the other end of the section, the wall C has a recess or pocket c³ that receives the interlocking projection c⁴. When the parts are in final assembled relationship, the interlocking recesses and projections just described serve to prevent relative lateral movement or accidental relative displacement of 90 the walls C and C'. Preferably, the tongue and groove construction of the two walls terminates at a slight distance from one end of the section in order to afford sufficient space for a joint with an adjacent section, and at this point, there is provided the extension or plate d which underlies the wall C' when the parts are locked together, as 95 shown in Figure 5.

In order to bring the two separable walls 105 together into interlocked relationship, the tongue c is inserted into the groove of the wall C in the manner shown in Figure 3. Then by holding the wall C' and moving the wall C longitudinally, at the same time 110 swinging the still separated end with the extension or plate d inwardly, and directing

the plate d under the wall C' the parts can readily be brought to the position illustrated in Figure 1, by exerting sufficient force to cause the projections c^2 and c^4 to spring into 5 the recesses c' and c^3 . The parts are thus held together tightly, and the separable walls cannot be accidentally displaced with relation to each other. When the pipe is 10 taken down, said walls can readily be spread apart by the reverse operation to that already described, namely, by swinging the end of section C with the plate d initially in a lateral direction, and then effecting a relative longitudinal movement of the walls C 15 and C' .

While I have described the invention with reference to a particular arrangement, I do not limit myself to the details shown, and this application is intended to cover any

modifications or departures coming within 20 the fundamental nature of the invention and the scope of the following claim.

I claim:

A pipe section comprising a main portion and a flue portion connected to and extended 25 laterally from the main portion, the main portion being split longitudinally from end to end at a point substantially opposite to the flue portion, said flue portion being larger at its base where it joins the main 30 portion and smaller at its outer end, with sufficient taper between its base and outer end to permit nesting one pipe section within another when the walls of the main portion are spread.

In witness whereof, I have hereunto signed my name.

WILLIAM GRAY.
